JAMES HOYT BROWN, OF NEW YORK, N. Y.

EYEGLASSES.

1,219,433.

Specification of Letters Patent. Patented Mar. 20, 1917.

Application filed May 5, 1915. Serial No. 25,989.

To all whom it may concern:

Be it known that I, JAMES HOYT BROWN, a citizen of the United States, and a resident of New York, in the county of New 5 York and State of New York, have invented certain new and useful Improvements in Eye-glasses, of which the following is a specification.

This invention relates generally to eye 10 glasses and particularly to the means for securing the mountings to the lens.

There are a number of difficulties to be overcome in securing eye glass mountings to the lens.

15 These difficulties are, first, to fit the mounting accurately and closely to the lens, and second, to hold or secure the mounting so tightly and permanently to the lens that it will not work loose while in use.

20 The first difficulty above mentioned arises from the fact that lens and mountings are subject to certain variations in size and arrangement which are apt to produce difficulty in making a close connection between them, and the second difficulty arises from 25 the fact that the types and arrangements of mountings heretofore employed are apt to work loose even when tightly adjusted in the first place, and this loosening action is 30 intensified if for any reason the initial adjustment of the mounting to the lens is not perfect.

The present invention is intended to overcome the foregoing difficulties by providing, 35 first, an accurate, and second, a strong and lasting, connection between the lens and the mounting.

With the foregoing and other objects in view which will appear as the description 40 proceeds, the invention resides in the combination and arrangement of parts and in the details of construction hereinafter described and claimed, it being understood that changes in the particular embodiment 45 of invention herein disclosed can be made within the scope of what is claimed, and as indicated by the variations in the claims, without departing from the spirit of the invention.

50 In the accompanying drawing forming part of this specification:

Figure 1 is a view in elevation of a pair of spectacles equipped with the present invention.

55 Fig. 2 is an enlarged sectional view

through one of the mountings and lens showing the lens in an edgewise section.

Fig. 3 is a view in elevation of one of the mountings, looking in the same direction as in Fig. 2, the lens being omitted. 60

Fig. 4 is a view of a fragment of a lens with a mounting applied thereto, the straps or shoe of the mounting being omitted.

Like reference numerals indicate corresponding parts in the different figures of the 65 drawing.

The lens of the eye glasses are indicated by the numerals 1—1. The bridge piece is indicated by 2. The temples or ear pieces are indicated by 3. The mountings by 70 means of which the lens, bridge and temples are secured together are indicated by 4.

Each lens 1 is slotted as indicated at 5, in any suitable manner, to receive the mounting 4. 75

Each mounting 4 is constructed preferably with a stud or body portion 6 to which either the bridge 2 or the temple 3 is connected according to whether it is a bridge or an end piece mounting. 80

Each mounting 4 is formed with a pair of lens-engaging ears 7—7 which engage opposite sides of the lens adjacent the slot 5. The ears 7 may be of any suitable shape and are of a size wider than the slot 5 so 85 as to be capable of being clamped in frictional engagement with opposite faces of the lens adjacent the slot.

For the purpose of securing the ears 7—7 against the lens and of holding them in position thereon I prefer to employ either a screw 8 shown in Fig. 2 or a rivet 9 as shown in Fig. 3. The screw or rivet extends through the ears and slot 5 in the lens. The screw or rivet is usually applied to the 95 mounting and in securing the mounting to the lens it is only necessary to push the mounting endwise onto the lens, the screw or rivet thus traversing the slot after which the screw is tightened or the rivet 100 is upset so as to clamp the ears 7 tightly in frictional engagement with the lens.

For the purpose of holding the mounting in line with the slot and preventing its moving on the screw 7 as a pivot, reliance may 105 be placed on either the projections 10—10 arranged on the inner faces of the ears 7 and fitting into the slot 5, or on the straps 11—11 of the mounting which engage the edge of the lens, and in connection with the 110

screw, will prevent pivoting of the mounting, or on both the projections 10 and the straps 11. For instance, in Fig. 1 both the projections 10 and the straps 11 are employed, but in Fig. 4 the straps 11 are omitted and only the projections 10—10 are employed.

For the purpose of facilitating the adjustment of the ears 7—7 to different shapes 10 or thicknesses of lens, the inner faces of the ears adjacent the body portion 6 are hollowed out or slightly rounded and narrowed as indicated at 12, for the purpose of avoiding square corners, with the result that, by 15 means of pliers, the ears can be readily shaped or pressed into close engagement with any type of lens.

The frictional engagement of the ears 7 with the lens 1 is not sufficient in itself to 20 produce a tight and permanent connection, and I make the engagement positive with the use of gritty particles such as emery, diamond dust or the like to be introduced between the ears 7 and the lens. When the 25 ears are drawn tight against the lens the powdered emery is embedded in the ears and the lens and forms a non-slip grip on the lens.

The emery or light gritty particles may 30 be used either alone or in combination with a suitable binder; such as shellac or liquid self-hardening cement; to enable the particles to be handled and applied to the lens mounting to better advantage. Of course, 35 the effect of the gritty particles is the same, whether they are used alone or in a binder, or cemented as stated.

As before stated, in some cases I may 40 rely on the straps 11 to coöperate with the friction grip of the ears and to hold the mounting against swinging movement on the screw, and in this case I may sometimes omit the projections 10; but I sometimes employ both the straps and projections, and I 45 really prefer to omit the straps as shown in Fig. 4, and rely entirely on the projections with emery, etc., between the lens and mounting.

A very important advantage to be secured 50 in providing a construction such as shown in Fig. 4 in which it is possible to dispense with the straps 11 is that I am enabled to employ very large lens in the glasses when desired. There is an increasing demand for 55 large lens; but the use of straps results in an increase in the total length of the bridge piece and bridge mountings and a consequent widening of the "pupillary distance" between the eyes making necessary the use 60 of relatively small lens. In my construction in which I can dispense with the straps and shorten the mounting I am enabled to narrow the pupilar distance to a minimum and thus permit the use of larger lens.

65 It is also to be noted from Fig. 2 that I

preferably space the projections 10 from each other to provide a gap therebetween. This enables me to adjust the ears toward each other in fitting narrow or thin lenses, without any interference such as would occur if the projections were close enough to abut or if a solid wall or partition were employed to connect the ears, in which case adjustment of the ears would be interfered with or prevented.

70 It is needless to say that the dispensing with the straps 11 and the shortening of the studs results in a great economy in precious metals and cost of manufacture.

75 Moreover, as usually manufactured the straps and ears are made in one piece, and the stud 6 is soldered thereto and the entire mounting is then hardened to give the necessary stiffness to the straps. This hardening of the mounting to stiffen the straps results 80 usually in too much hardening of the ears, which are consequently liable to be brittle and break in attempting to re-shape the ears to fit different sizes of lens. In my construction wherein the straps can be dispensed with, the mounting can be made in one piece, or in the usual way, if desired, and as there 85 are no straps to be stiffened, with my form of mounting a more soft and pliable metal can be employed, with the result that the ears can be worked into different shapes with less liability to breakage than heretofore.

90 It is to be understood that it is not necessary to use both projections on the ears as one projection will serve the purpose.

95 It is to be noted from Fig. 2 that I sometimes employ three projections 10 to engage the slot 5 and hold the mounting against turning. I may also omit any two of these 100 three projections 10—10—10— as any one of these will serve the purpose, and the omission of the others will result in a saving of precious metal.

105 It is also to be noted that I sometimes sprinkle a small quantity of diamond dust, powdered emery or other non-slip substance around the socket of the head of the screw 8 before turning such screw home. I find that such dust serves to lock the screw 110 against loosening movement.

115 What is claimed as new is:

1. The combination of a lens, a mounting, emery dust or like gritty material interposed between and engaging said lens and mounting to resist slipping.

120 2. The combination of a lens, a mounting, and gritty particles between the lens and mounting to provide frictional engagement between the said parts.

125 3. The combination of a lens, a mounting having ears to receive the lens between them, means for causing the ears to hold the lens, and gritty particles between the ears and the opposite faces of the lens to provide frictional engagement between said parts.

4. The combination of a lens having an open-ended recess in its edge, a mounting comprising ears to receive the lens between them, a tightening element carried by the ears to cause the ears to hold the lens, one or more projections carried by the mounting in line with said element and adapted to be inserted with said element into said open-ended recess, and gritty material between the ears and the opposite faces of the lens, whereby, when the tightening element is operated, the lens and the mounting will be held together and the lens prevented from turning about said element as a pivot.
5. The combination of a lens having an open ended recess in its edge, a mounting comprising ears to receive the lens between

them, a tightening element carried by the ears to cause the ears to hold the lens, and one or more projections carried by the 20 mounting in line with said element and adapted to be inserted with said element in said open ended recess and fit said recess snugly, whereby, when the tightening element is operated, the lens and mounting will 25 be held together and the lens prevented from turning about said element as a pivot.

Signed at New York in the county of New York, and State of New York this 4th day of May A. D. 1915.

JAMES HOYT BROWN.
